(57) **CLAIM**

The ornamental design for an exhale smoke filter, as shown and described.

DESCRIPTION

FIG. 1 is a perspective view of an exhale smoke filter showing my new design with two connected end caps attached to the filter;

FIG. 2 is a perspective view of the exhale smoke filter shown in FIG. 1 with the two connected end caps detached from the filter;

FIG. 3 is a front view of the exhale smoke filter shown in FIG. 1 with the two connected end caps attached to the filter;

FIG. 4 is a front view of the exhale smoke filter shown in FIG. 1 with the two connected end caps detached from the filter;

FIG. 5 is a right side view of the exhale smoke filter shown in FIG. 1 with two connected end caps attached to the filter;

FIG. 6 is a left side view of the exhale smoke filter shown in FIG. 1 with two connected end caps attached to the filter;

FIG. 7 is a right side view of the exhale smoke filter shown in FIG. 1 with two connected end caps detached from the filter;

FIG. 8 is a left side view of the exhale smoke filter shown in FIG. 1 with two connected end caps detached from the filter;

FIG. 9 is a top perspective view of the exhale smoke filter shown in FIG. 1 with two connected end caps detached from the filter;

FIG. 10 is a top view of the exhale smoke filter shown in FIG. 1 with two connected end caps attached to the filter;

FIG. 11 is a top view of the exhale smoke filter shown in FIG. 1 with two connected end caps detached from the filter;

FIG. 12 is a bottom view of the exhale smoke filter shown in FIG. 1 with two connected end caps attached to the filter; and,

FIG. 13 is a bottom view of the exhale smoke filter shown in FIG. 1 with two connected end caps detached from the filter. The evenly spaced broken lines appearing to be the interior portion of the exhale smoke filter in FIG. 13 show portions that form no part of the claimed design.
